(57) **CLAIM**

The ornamental design for a supporting stand for mobile computer, as shown and described.

DESCRIPTION

FIG. 1 is a top front left perspective view showing a first embodiment of my new design;

FIG. 2 is a top rear right perspective view showing a first embodiment of my new design;

FIG. 3 is a bottom rear left perspective view showing a first embodiment of my new design;

FIG. 4 is a front view of the first embodiment of my new design;

FIG. 5 is a rear view of the first embodiment of my new design;

FIG. 6 is a left side view of the first embodiment of my new design;

FIG. 7 is a right side view of the first embodiment of my new design;

FIG. 8 is a top view of the first embodiment of my new design;

FIG. 9 is a bottom view of the first embodiment of my new design;

FIG. 10 is a top front left perspective view of the first embodiment of my new design to the folded state;

FIG. 11 is a top front left perspective view of the first embodiment of my new design with a bulletproof vest and mobile computer;

FIG. 12 is a top front left perspective view showing a second embodiment of my new design;

FIG. 13 is a top rear right perspective view showing a second embodiment of my new design;

FIG. 14 is a bottom rear left perspective view showing a second embodiment of my new design;

FIG. 15 is a front view of the second embodiment of my new design;

FIG. 16 is a rear view of the second embodiment of my new design;

FIG. 17 is a left side view of the second embodiment of my new design;

FIG. 18 is a right side view of the second embodiment of my new design;

FIG. 19 is a top view of the second embodiment of my new design;

FIG. 20 is a bottom view of the second embodiment of my new design;

FIG. 21 is a top front right perspective view of the second embodiment of my new design to the folded state; and,

FIG. 22 is a top front right perspective view of the second embodiment of my new design with a bulletproof vest and mobile computer.

(Continued)

The broken lines shown in the drawings represent portions of the supporting stand for mobile computer that form no part of the claimed design.
